COMBINED PROJECTOR AND VIEWING
ATTACHMENT FOR MICROSCOPES OR
SIMILAR ARTICLES

Harry Preble, Jr., Cross River, N.Y., assignor to The
A. C. Gilbert Company, New Haven, Conn., a corpo-
ration of Maryland

Filed July 20, 1962, Ser. No. 70,997

Term of patent 14 years

(Cl. D57—7)

FIG. 1 is a perspective view of combined projector and viewing attachment for microscopes showing my new design;

FIG. 2 is a front elevational view thereof;

FIG. 3 is a side elevational view thereof;

FIG. 4 is a rear elevational view thereof;

FIG. 5 is a top plan view thereof; and

FIG. 6 is a bottom plan view thereof.

The side not shown is substantially the same as the side shown.

I claim:

The ornamental design for a combined projector and viewing attachment for microscopes or similar articles, substantially as shown and described.
